UNITED STATES PATENT OFFICE.

FRIEDRICH GEORG WINKLER, OF ZSCHOPPAU, SAXONY, GERMANY, ASSIGNOR
TO ROBERT E. LESTER, OF NEW YORK, N. Y.

SIFTING-MACHINE.

SPECIFICATION forming part of Letters Patent No. 400,621, dated April 2, 1889.

Application filed November 22, 1888. Serial No. 291,597. (No model.)

To all whom it may concern:

Be it known that I, FRIEDRICH GEORG WINKLER, of Zschopau, Saxony, Germany, have invented certain Improvements in Sifting-Machines, of which the following is a specification.

These improvements relate to the type of cylindrical sifting-machines in which the sifting operation is performed by means of inward and outward vibratory movements of air propagated progressively around the entire sieve.

These improvements embrace the employment, in a sifting-machine, of the type above referred to, first, of a single-wave generator as distinguished from the multiple-wave generators described in another pending application for a patent, whereby the diameter necessary for the rotating structure is diminished and the size of the machine as a whole is correspondingly reduced; secondly, of a deflecting-grate composed of a cylindrically-arranged system of bars, the spaces between which bars are approximately diagonal relatively to the radii of the rotating structure, and the width of which at the outer surface of the grate does not exceed their width at the inner surface of the grate; thirdly, of a spiral scraper affixed to the shaft of the rotating wave-generator and operating to prevent the collection of flour-dust or other material in the annular spaces between the said shaft and the hollow hubs of the rotating deflecting-grate.

The accompanying drawings of a flour-bolting machine containing the improvements are as follows:

Figure 1 is a central vertical longitudinal section. Fig. 2 is a transverse vertical section taken through the plane indicated by the line $x-x$ on Fig. 1. Fig. 3 is a full-sized transverse section of a portion of the deflecting-grate.

The apparatus represented in the drawings consists of a bolting-chest, A, within which is a rotating cylindrical sieve, B, mounted upon the disks b and b' , the hollow hubs b' and b^2 of which are seated, respectively, in bearings b^3 and b^4 . Within the rotating sieve is a rotating deflecting-grate, C, supported upon the peripheries of two disks, C' and C^2 , provided with hollow hubs C^3 and C^4 , respectively pro-

vided with bearings C^5 and C^6 at the ends of the machine. Within the cylindrical deflecting-grate is a rotating wave-generator, D, 55 which is mounted upon the swift-running shaft E, journaled at its opposite ends, respectively, in the bearings e and e' , and provided with the fast and loose pulleys E' and E^2 for engaging the belt by which the wave-generator is rotated. The hollow hub C^4 of the rotating deflecting-grate is provided with the driving-pulley C^7 . The hollow hub b' of the sieve is provided with the driving-pulley B^2 . The portions of the shaft E which are contained within the hollow hubs C^3 and C^4 are provided, respectively, with the spiral blades e^2 and e^3 , for preventing the retention of flour-dust or other substance in the annular spaces between the said portions of the shaft E and the interior surfaces of the hollow hubs C^3 and C^4 .

The deflecting-grate is composed of preferably parallel and equidistantly-arranged bars, each consisting of a slat, i , which is diagonally inclined with relation to the radius of the rotating structure, and which is provided upon its outer side with a radially-projecting strip, i' . The space between the outer portions of the slat i and the radially-projecting strip i' may be filled up solid, in which case the outer portion of the slat will have the form of the prism i^3 , (shown in Fig. 3;) or it may be left unfilled, in which case it will constitute the recess i^4 . (Shown in Fig. 3.)

The single-wave generator is composed of two parallel disks, D' and D^2 , affixed to a central shaft, D^3 , and united to each other by a fan extending longitudinally across the generator from one disk to the other. Like the double-wave generators described in pending application, No. 291,549, filed November 22, 1888, the fans of the single-wave generators may be arranged in a great variety of ways. One of the more simple forms is illustrated in Fig. 2, 90 in which, as will be seen, a fan consisting of a partition, d , extending radially inward from the periphery of the generator part way to the shaft, and having its inner edge, d' , united to or formed in one piece with a sheet of metal, d^2 , so curved that its cross-section has a scroll shape, as represented in Fig. 2, and which has its edge d^3 united to the outer edge of the radial partition d .

The direction of rotation is indicated by the concentrically-curved arrow d^5 . As the fan rotates, the air gathered within the gradually-narrowing space between the deflecting-grate 5 and sieve and the advancing eccentrically-curved surface d^6 of the fan is ejected in a radially-outward direction, as indicated by the group of radially-arranged outwardly-pointing arrows. The fan may be considered as 10 composed of the radial partition d and of the adjoining portion d^3 of the curved partition. In front of the advancing fan the air is compressed, and in the rear of the advancing fan a partial vacuum is established. A certain 15 quantity of air is ejected radially from the generator through the deflecting-grate and the portion of the sieve between a line radially opposite the apex of the fan and a parallel line at a distance of, say, forty-five degrees 20 therefrom, more or less. A quantity of air equal to that thus ejected is at the same time admitted through the remaining three-quarters of the sieve and through the deflecting-grate into the generator, as indicated by the 25 inwardly-pointed arrows. It will therefore be seen that the rotation of the fan propagates around the entire sieve a single wave composed of vibrations or outward currents of air of high pressure ejected through a comparatively 30 small portion of the sieve and inward currents of low pressure which concurrently flow inward through a relatively large portion of the sieve.

By means of deflecting-bars the outward 35 currents are deflected radially toward the sieve with sufficient force to press the finer particles of material operated upon directly through the meshes, while the coarser materials which, having been thrown against the 40 interior of the sieve, may have lodged thereon, are dislodged by the inward currents of air, and are caught upon the outer surfaces of the deflecting grate-bars.

The direction of rotation of the deflecting-grate is preferably opposite that of the wave-generator. The particles which, being thus driven inward, catch upon the grate-bars, are immediately thrown outwardly therefrom toward the sieve and are again thrown inward 45 by the internal pressure of the external air. The inward currents of air therefore prevent the interior surface of the sieve from becoming clogged by progressively clearing from obstructions the part of the sieve which is about 50 to be subjected to the action of the outgoing currents.

The uniform clearance of all portions of the interior surface of the sieve is insured by the establishment within the sieve of a continuous 55 air-current in a path concentric with and extending around the greater portion of the interior surface. The establishment of this concentric current is permitted by the use of the single-wave generator, which leaves nearly 60 the whole of the interior of the sieve-cylinder unobstructed. It results that, in addition to the radially-inward pressure of the external

air tending to dislodge the bran or coarser particles from the inner surface of the sieve, there exists another important factor in effecting the clearing of the sieve—to wit, the interior concentric air-current, which tends to sweep the bran from the inner surface of the sieve. 70

It will be perceived that for the successful 75 operation of sifting apparatus of the type herein referred to it is necessary that there shall be continuously supplied to the interior of the wave-generator the quantity of air required to furnish the outgoing current, and, as the inward current is of comparatively 80 low pressure, a relatively considerable area of the sieve must be devoted to the purpose of admitting it; but by the employment of a single-wave generator and the resulting 85 larger proportion of the sieve which is thereby left available for admitting the inward current of air of low pressure, the diameter of the rotating structure can be diminished, and the size of the machine as a whole, therefore, 90 be correspondingly reduced.

The single-wave generator can be rotated more rapidly than a double-wave generator of like diameter, and still a sufficient quantity of air be supplied to the interior of the 95 generator to furnish the amount required for the outgoing current. It therefore follows that by the use of a single-wave generator the machine, as a whole, can be reduced in size 100 without impairing its sifting capacity.

I claim—

1. The combination, with a cylindrical sieve, of a single rotating wave-generator for continuously propagating a single wave of air around the entire circumference of said cylindrical sieve, the said generator consisting, essentially, of two parallel disks affixed to a central shaft and of a fan extending inwardly from one side of the periphery of the generator, and extending longitudinally across the 110 generator from one of said disks to the other.

2. In combination with a cylindrical sieve and means for establishing outward and inward currents of air through said sieve, a hollow cylindrical deflecting-grate composed 115 of a system of slats inclined diagonally with relation to the radial lines, which centrally intersect them, respectively, and shaped in cross-section, substantially as described, whereby the widths of the outer ends of the 120 spaces between the slats are prevented from exceeding the widths of the inner ends of the said spaces.

3. The combination, as herein set forth, of the hollow hubs C^3 and C^4 , of the cylindrical deflecting-grate and the spiral blades e^2 and e^3 , affixed to the portion of the fan-shaft E which is surrounded by the said hubs, respectively. 125

FRIEDRICH GEORG WINKLER.
